DESIGN FOR A HAT

Joseph Cohn, New York, N. Y.

Application January 14, 1941, Serial No. 93,033

Term of patent 7 years

To all whom it may concern:

Be it known that I, Joseph Cohn, a citizen of the United States, residing at 1100 Park Avenue, in the city of New York, county of New York, State of New York, have invented a new, original, and ornamental Design for a Hat, of which the following is a specification, reference being had to the accompanying drawing, forming part thereof.

Fig. 1 is a front perspective view of a hat showing my new design.

Fig. 2 is a rear view in perspective of the hat shown in Fig. 1.

Fig. 3 is a view in perspective looking into the hat.

I claim:

The ornamental design for a hat, substantially as shown.

JOSEPH COHN.
